PIN CURL FORMING DEVICE

Otto F. Trippler, East Detroit, Mich.

Application March 29, 1950, Serial No. 152,614

2 Claims. (Cl. 132—33)

1

This invention relates to hair curling devices, and, in particular, to pin curl forming devices.

One object of this invention is to provide a pin curl forming device which in a simple and effective manner forms a pin curl, holds the pin curl while a so-called bobby-pin is inserted with its legs passing above and below the pin curl, and then releases the pin curl, leaving the bobby-pin in a clamping position on the pin curl.

Another object is to provide a pin curl forming device having a rotatable rod with a curl holding slot and a slidable guide or curl holder for not only holding the curl in position after it has been wound around the rod, but also for guiding the legs of the bobby-pin while they are being inserted below and above the curl.

Another object is to provide a pin curl forming device of the foregoing character wherein the slider has arms for holding down the pin curl being formed and also for guiding the legs of the bobby pin into the slot in the slider and rod, the arms being spaced apart from one another circumferentially a sufficient distance to permit the insertion of the finger-tips when holding the bobby-pin up to the edge of the guide slot, the circumferential widths of the spaces between the arms being a plurality of times greater than the circumferential widths of said arms thereby enabling the bobby-pin to be pushed completely into position with its legs below and above the pin curl without interference from any portion of the curl holder.

Another object is to provide a modified pin curl forming device of the foregoing character wherein the curl holder or slider has wings which are especially well adapted for use with a magazine bobby-pin holder.

Another object is to provide a pin curl forming device of the foregoing character having a ledge or shoulder thereon adapted to assist the user in opening the bobby-pin prior to its insertion below and above the pin curl.

In the drawings:

Figure 1 is a side elevation of a pin curl forming device, according to one form of the invention;

Figure 2 is a cross-section through the pin curl forming device taken along the line 2—2 in Figure 1;

Figure 3 is a cross-section taken along the line 3—3 in Figure 1;

Figure 4 is a cross-section taken along the line 4—4 in Figure 1;

Figure 5 is a fragmentary perspective view showing the pin curl forming device of Figure 1 at the start of the operation of forming a pin curl;

Figure 6 is a fragmentary side elevation, partly in vertical section, of the pin curl forming device of Figures 1 to 5 inclusive at the end of the curl forming operation, with the bobby-pin inserted and the device ready to be withdrawn;

Figure 7 is a fragmentary side elevation of a portion of a pin curl forming device, similar to Figure 1 but employing a modified curl holder or slider;

Figure 8 is a cross-section taken along the line 8—8 in Figure 7;

Figure 9 is a fragmentary side elevation similar to Figure 7 but showing a further modified curl holder or slider; and

Figure 10 is a horizontal section taken along the line 10—10 in Figure 9.

Referring to the drawings in detail, Figure 1 shows a pin curl forming device, generally designated 10 as consisting generally of a curl forming rod or body 11 having a curl holder 12 slidably mounted thereon and a dividing or blocking comb 13 mounted on the upper end of the rod 11. The rod 11 is preferably of circular cross-section with one or more longitudinal grooves 14 extending lengthwise thereof. Extending inward from the lower end 15 of the rod 11 are one or more slots 16, two slots 16 crossing one another at right angles being the preferred arrangement, although a single slot can also be used. The slots 16 at their upper ends 17 have end walls 18 inclined downward and inward toward the center 19 thereof.

Slidably mounted on the rod 11 is the tubular sleeve portion 20 of the curl holder or slider 12, the portion 20 having projections 21 extending inward into the slots 16 so as to permit longitudinal sliding without rotation of the curl holder 12. The sleeve portion 20 is provided with guide slots 22 aligned with the slots 16 in the rod or body 11, the sides 23 of the slots 22 being preferably flared (Figure 2) to facilitate insertion of the bobby-pin P. The curl holder 12 is also provided with a plurality of arms 25 projecting outward from the sleeve portion 20 and having curved base portions 26 leading inward from the arms 25 to the slots 22 so as to guide the bobby-pin into the slots 26 and 16 in the event that it strikes to one side or the other of the slots 22. The arms 25 have bottom portions 27 adapted to rest upon the curl C (Figure 6) and prevent it from slipping or unwinding while the bobby-pin is being inserted. Mounted on the upper end 28 of the rod or body 11 is a dividing comb 29. The circumferential widths of the spaces between the arms 25 (Figure 2) are a plurality of times the

circumferential widths of the arms 25 themselves, so that the relatively wide spaces between the relatively narrow arms 25 permit the fingers to be inserted between the arms 25 while inserting a bobby pin, without interference with the arms 25.

The modification, generally designated 30, shown in Figures 7 and 8, has a body or rod 11 similar to the rod 11 of Figures 1 to 6 inclusive and therefore similarly designated as to its component parts, including the grooves 14. Slidably mounted on the body 11 is a modified curl holder or slider 31. This consists of a sleeve portion 32 having pins 33 inserted therein and projecting into the longitudinal grooves 14 of the rod 11. Secured to the sleeve portion 32 are the longitudinal portions 34 of L-shaped wings 35, the lateral portions 36 of which project outward radially from the sleeve portion 32. The curl holder 31 is provided with longitudinal guide slots 37 arranged between the longitudinal wing portions 34 and aligned with the rod slots 16, as in the form of the invention shown in Figures 1 to 6 inclusive. The lateral wing portions 36 have rounded ends 38 and are spaced apart from one another a sufficient distance to permit the fingers to be inserted between them while inserting a bobby-pin.

The modification, generally designated 40, shown in Figures 9 and 10, likewise employs the same body or rod 11 with its longitudinal grooves 14 and has a curl holder or slider 41 provided with a sleeve portion 42 having, as before, pins 43 projecting into the slots 14 to prevent rotation (Figure 10). Radiating outward from the sleeve portion 42 at the lower end thereof are wings 44 having upturned edges 45 serving to guide a bobby pin into a longitudinal slot 46 similar to the longitudinal slots 22 and 37 of Figures 1 and 7 respectively and similarly aligned with and guiding a bobby pin P into the slot 16 in the lower end of the rod 11. The modification 41 of Figures 9 and 10 is especially well adapted for use with a magazine bobby-pin holder of the type described and claimed in my co-pending application Serial No. 166,883 filed June 8, 1950 for Magazine Bobby-Pin Holder, now abandoned.

In the use of the form of the invention shown in Figures 1 to 6 inc., the operator grasps the upper portion of the rod 11 with the slider or curl holder 12 drawn upward to expose the slots 16 and positions the body 11 approximately tangentially to the head H of the person whose hair is to be curled (Figure 5). The operator then uses the comb to divide the hair and separate a lock L, the free end of which he or she inserts through one of the slots 16. The operator then rolls the lock L into a coil by rotating the body or rod 11 in his or her fingers, thereby forming the curl C. When the lock L is fully wound on the rod 11 to form the curl C, the operator then turns the rod 11 into a position substantially radial or perpendicular to the head H and at the same time brings the lower end 15 into contact with the scalp in the manner shown in Figure 6.

The operator then slides the curl holder or slider 12 downward into engagement with the curl C so as to hold the curl firmly against the head H while the bobby pin P is inserted. To insert the bobby pin P, the operator first separates the legs A, inserting the lower leg against the scalp beneath the curl C and the upper leg above it (Figure 6). If the person whose hair is being curled is forming the curls herself, without outside assistance, she is assisted in inserting the

legs A of the bobby pin P by the converging sides and curved portions 26 of the arms 25 (Figure 2) and also by the flared sides 23 of the slots 22. These portions serve to guide the ends of the legs

5 A into the slots 22 and thence into the slots 16 in the rod 11. Since the arms 25 are spaced approximately 90° apart and the circumferential widths of the spaces between them are a plurality of times the circumferential widths of the arms 25 (Figure 2), the fingertips holding the closed end E of the bobby pin P can be inserted as far as the slot 22 without interference from the arms 25, thereby permitting the bobby pin P to be fully inserted.

When the bobby pin P has been fully inserted, the operator releases the upper leg A which, by reason of the resilience of the bobby pin, snaps downward into the dotted line position shown in Figure 6. The operator then lifts the rod 11 out of the curl C, leaving the curl held in position by the bobby pin P. Since two slots 16 are provided at right angles to one another, a second bobby pin P can be inserted at right angles to the first one before withdrawing the pin curl forming device 10, using the same procedure described in connection with the first bobby pin P. The use of the modifications 30 or 40 is substantially similar to that of the pin curl forming device 10 and requires no additional description. The sliders or curl holders 31 and 41 are conveniently made of metal, whereas the curl holder 12 is preferably made of plastic, along with the rod or body 11. As previously stated, the pin curl holder 41 is especially adapted for use with a magazine bobby-pin holder from which a number of pins can be inserted one after the other in the curls C in the manner described in my above-identified co-pending application.

Instead of providing grooves 14 in a rod 11 of circular cross-section, in order to prevent rotation of the curl holder 12 on the rod 11, it will also be obvious that a rod 11 and curl holder 12 of non-circular cross-section may be used for this purpose: for example, a rod of square, oval, triangular or other polygonal cross-section. A rod of circular cross-section having a flat longitudinal side portion may also be used to prevent rotation of the curl holder, which is provided with a bore having corresponding portions.

What I claim is:

1. A pin curl forming device comprising a rod-like curl forming member having a diametrically-disposed curl-receiving slot extending transversely therethrough and into its interior from one end thereof, and a curl holding member having a sleeve portion slidably mounted on said curl forming member and having a bobby-pin guide slot therein alignable with said curl-receiving slot, said curl holding member having a plurality of circumferentially-spaced relatively narrow curl holding arms diverging outwardly from said guide slot, the circumferential widths of the spaces between said arms being a plurality of times the circumferential widths of said arms, the inner end portions of said arms being curved toward the sides of said guide slot.

2. A pin curl forming device comprising a rod-like curl forming member having a diametrically-disposed curl-receiving slot extending transversely therethrough and into its interior from one end thereof, and a curl holding member having a sleeve portion slidably mounted on said curl forming member and having a bobby-pin guide slot therein alignable with said curl-receiving slot, said curl holding member having a plurality

of circumferentially-spaced relatively narrow curl holding arms diverging outwardly from said guide slot, the circumferential widths of the spaces between said arms being a plurality of times the circumferential widths of said arms, the inner end portions of said arms being curved toward the sides of said guide slot and the sides of said guide slot being flared outwardly toward said curved portions of said arms.
